FILLING-REPLENISHING LOOM.

1,290,661.

Specification of Letters Patent.

Patented Jan. 7, 1919.

Application filed May 4, 1915. Serial No. 25,710.

To all whom it may concern:

Be it known that I, ALONZO E. RHOADES, a citizen of the United States, residing at Hopedale, county of Worcester, and State 5 of Massachusetts, have invented an Improvement in Filling-Replenishing Looms, of which the following description, in connection with the accompanying drawings, is a specification, like characters on the drawings representing like parts.

The invention to be hereinafter described relates to filling replenishing looms, and more particularly to the means for preventing the ends of filling being carried into the 15 shed.

In looms of this general character, when replenishment of the filling is effected, prior to the complete exhaustion of the filling in the running shuttle, there is an end of filling 20 leading from the outgoing filling carrier to the cloth selvage, which is generally denominated the "old filling"; and there is another filling end leading from the fresh filling carrier to some securing means where 25 the end of the new filling is secured, and such length of filling is generally denominated the "new filling" end.

Various attempts have been made with 30 more or less success, to prevent the old filling end from being carried into the shed after a replenishing operation, and some efforts have been made to effect a similar result with respect to the new filling end. In all these latter attempts, however, the new filling 35 end has been parted at a point so far from the place where the end of the new filling was secured, that a long end of new filling dangled from the securing means and was liable, during the back-and-forth movement of the lay, to be caught by the shuttle or the working filling, and be carried into 40 the shed.

With the above generally-stated facts in mind, the aims and purposes of the present 45 invention are to provide means whereby the new filling end may be parted at such point that the end of new filling dangling from the securing means cannot be caught by any of the operating parts, or by the working 50 filling, and consequently cannot be carried into the shed. Another important feature of the invention in connection with the parting means referred-to, is the provision be-

tween the selvage or temple thread cutter and said parting means of means for carrying out of the loom the piece of new filling after it has been parted from the securing means and the cloth selvage.

A further purpose of the present invention is to provide parting means for the new 60 filling end which shall be set for action only upon call for filling replenishment, and shall thereupon part the new filling on the forward movement of the lay subsequent to the replenishing operation.

The present invention also embodies other 65 important features, all of which will be more fully understood from the following description and accompanying drawings of one form of means for carrying the invention into practical effect, it being understood that the details may be varied within the 70 true scope of the actual invention.

In the drawings:—

Figure 1 is a view looking toward the end 75 of the loom at the filling replenishing side, some of the parts being broken away for clearness of illustration;

Fig. 2 is a front view at the filling 80 replenishing side of the loom with the filling replenishing mechanism and its associated parts omitted for the purpose of clearness of illustration; and

Fig. 3 is a sectional plan view on the line 85 3—3 of Fig. 1, the general relation of the parts being indicated as the lay moves to its front or beating up position.

Fig. 4 is a perspective view of parts at the filling replenishing side of the loom showing the hopper, the securing means for 90 the ends of the new filling, the parter, and associated elements, some of the hopper stand or bracket being broken away to disclose parts beyond.

The frame of the loom may be of any 95 suitable character for supporting the operating parts, and as shown comprises the usual standards or uprights 1, and breast beam 2.

The filling replenishing mechanism may 100 be of any usual or desired character, but as herein shown, it comprises the hopper stand or bracket 3 rising from a base plate 4 which may be secured to the breast beam 2, as by suitable bolts 5. Pivotally mounted at 6 105 upon the usual supporting stud is the trans-

ferrer 7, the end 8 of which is adapted to engage a filling carrier 9 mounted as usual in a rotary hopper 10 supported by the hopper stand or bracket 3 as usual. A portion of one end of the hopper is shown at 10, Figs. 1 and 3. Depending from the transferrer 7 is the arm 11 having the dog 12 pivotally secured thereto, as usual, and adapted when in raised position to be engaged by a 10 suitable bunter 13 carried by the lay to cause the transferrer to transfer a filling carrier from the rotary hopper 10 to the shuttle in the shuttle-box beneath and by such action also, to eject the spent or practically-exhausted filling carrier.

The positioning of the dog 12 is effected from the transverse shaft 14, Figs. 1 and 4, as the latter is rocked by well-understood mechanism when the usual indicator indicates substantial or complete exhaustion of filling in the active shuttle. The arm 15, the spring 16, the arm 17 pivoted at 18 and having a finger 19 and the connection of the arm 17 with the dog 12 as at 20, may all 25 be as usual, and since such parts and their operative relation are well understood by those skilled in the art, further elucidation herein is unnecessary.

One of the purposes of the present invention 30, as hereinbefore indicated, is to part the new filling end at such point that the portion thereof which extends from the securing means for the end, cannot be engaged by any of the operating parts and be carried into the shed. To this end, it is within the contemplation of the invention that the parting means for the new filling end shall part such filling end after a filling replenishing operation at a point nearer to the securing means for said end than the distance between the said securing means and the lay or shuttle-box. Under these conditions, it will be apparent that the end which is held by the securing means after the new 45 filling has been parted, cannot reach any of the operating parts, and consequently, danger of its being carried into the shed is entirely overcome. The part of the new filling between the cloth selvage and the point 50 at which it has been parted, as hereinbefore noted, is subjected to the action of a controlling means such that as soon as the new filling has been parted at the point designated, the loose end leading from the cloth 55 selvage is at once drawn away from the operating parts of the loom and when such loose end is parted from the cloth selvage, it is bodily carried out of the loom, or away from all danger of being engaged and carried into the shed.

In carrying the invention into effect, the parting means is formed of two relatively movable members which are preferably maintained in closed or inoperative relation 65 during the normal operations of the loom,

and are separated or placed in position for performing their parting function upon call for filling replenishment.

In carrying this feature of the invention into effect, the hopper stand or bracket 3 is 70 provided with a guideway 21 extending from the front toward the rear portion of the hopper stand, as indicated in Figs. 2 and 3, and in said guideway 21 there is mounted the parter operating member shown herein 75 as a rod 22 Figs. 2 and 3 extending toward the rear of the loom in the guideway 21 and having secured to or formed as part of its rear end portion, a parting or cutting member 23, Figs. 1 and 4. This parting or cutting member 23 is preferably slotted, as at 24, Fig. 3, to straddle the stationary parting or cutting member 25 Figs. 1 and 3 when the cutting member 23 performs its parting stroke, as will hereinafter more fully appear.

The stationary member 25 of the parter is preferably formed as a plate secured by appropriate means such as the screws 26 in a recess or cut-away portion of the hopper stand 3, substantially as indicated in Fig. 3, the construction being such that when the parting or cutting member 23 moves to the front from the position indicated in Fig. 1, the stationary member 25 will enter the slot 24 of the member 23 and the new filling end a will be parted, as will readily be apparent from Fig. 1.

Extending downwardly from the rod 22 is a head 27, Figs. 1 and 4, having a facing 28 of yielding material, such as leather, rubber, or the like, to be engaged by a bunter 29 carried by the lay. The head 27 is normally under the influence of a spring 30 which tends to move the rod 22 and its attached parting member 23 rearwardly, when said rod and parting member are free to movement. This spring 30 may preferably be seated in a recess 31 formed in the hopper stand, one end of said spring being seated 100 upon a wall at the end of the recess 31 and the other end of the spring against the head 27, substantially as indicated in Fig. 1, the construction being such that the spring 30 105 normally acts upon the head 27 to project it 110 upon the connected rod 22 and the parting member 23 toward the rear of the loom.

The rod 22 is provided with a notch 32 near its outer end, adapted to be engaged by a latch 33 pivoted at 34 Fig. 2 to the base portion 4 of the hopper stand, a spring 35 normally acting upon the latch 33 to move it into engagement with the notch in the rod 22, the construction being such that when the rod 22 is moved toward the front 115 of the loom and the movable member 23 of the parting device is moved toward and into 120 co-operative relation with the fixed member 25 thereof, the latch 33 will drop into the recess 32 of the rod 22 and thereafter main- 125

tain the rod and its attached movable member 23 toward the front of the loom.

The condition of parts described is that which they maintain during the normal operation of the loom, that is, while a sufficient supply of filling is present for weaving purposes; and it will be noted that the fixed and movable members of the parter are then in closed relation, substantially as indicated 10 in Fig. 3. When, however, a call for filling replenishment is made, it is the purpose of the present invention that the fixed and movable members of the parter shall be relatively moved into the position substantially 15 as indicated in Fig. 1; and as a convenient means to this end, there is mounted upon the transverse shaft 14, a rocker arm 36, the upper portion of which is provided with a lifting cam 37 normally positioned below the 20 end 38 of the latch 33, the construction being such that when the transverse shaft 14 is rocked contraclockwise, viewing Fig. 1, upon call for filling replenishment, the lifting cam 37 will lift the end 38 of the latch 25 33 and free the rod 22 to the action of the spring 30, whereupon the latter will move the rod and its attached movable parting member 23 to the rear into substantially the position indicated in Fig. 1.

30 The extreme front end portion of the rod 22 is provided with an incline 39, Fig. 3, so that upon forward movement of the rod 22 after the replenishing operation and the new filling has been parted, such incline 35 portion 39 will lift the end 38 of the latch 33 until the arrival of the notch 32 beneath the latch, whereupon the latter will drop into its locking position, substantially as hereinbefore described, it being understood, of course, that the rocker arm 36 at such time will have moved clockwise again to carry the low part of the cam 37 beneath the end 38 of the latch, thereby permitting the above control of parts.

40 In order that the latch 33 may be properly guided and steadied in its movements, under the action of the spring 35, and the cam 37, it is embraced by the two steadyng posts 40, Figs. 1 and 2, which may be appropriately secured to the base portion of the hopper stand, as by screws or other means 41.

As hereinbefore noted, it is one of the purposes of the present invention that the 55 end of the filling which may hang or dangle from the securing means for the said end after the new filling has been parted, shall not be caught by any of the moving parts and pulled from the securing means or 60 broken and carried into the shed.

In effectively carrying out this feature of the invention, the ends of the fillings leading from the carriers 9 which are mounted in the rotary hopper 10, are secured to appropriate securing means to hold this end

of the filling as the shuttle is picked after the replenishing operation; and the parting mechanism is located with respect thereto so that after its action, the end of the filling held by the securing means cannot 70 reach the operative parts of the loom, which would endanger its being carried into the shed. As one appropriate and good form of securing means to this end, the rotary hopper 10 is provided with a series 75 of spring-actuated securing pins 42, Figs. 1 and 3, which are adapted to hold the ends *b* of the new filling extending from the carriers in the hopper. Ordinarily there will be sufficient slack in the filling between the 80 securing means, such as the pins 42, and the carriers in the hopper to permit the carriers to be transferred to the shuttle without breaking the filling, but in the present instance of the invention a guide or deflector 42^a, Figs. 1 and 4 is provided on the hopper adjacent each filling carrier in the hopper. The filling from the carriers may be passed over the guide or deflector 420 near the tip end of the filling carriers 85 in the hopper, then about the guide or deflector 420 near the base of the filling carriers or it may be passed about only one of these guides or deflectors and then secured to the pins or other securing means 42 mounted 90 on the head of the rotary hopper. In either case the guides or deflectors insure sufficient slack thread for the transfer without liability of breakage.

The spring-holding pins 42 are preferably of appropriate number and mounted on the rotary hopper 10 to provide for holding all of the filling ends leading from the carriers in the hopper, and it will be evident that when the filling has been parted 100 by the parting members 23 and 25, the end of the piece of filling *b* hanging from the securing means or pins 42, cannot reach the lay or shuttle-box, because such filling has been severed at a point between the 105 hopper or hopper stand and the top of the shuttle-box. On rotary movement of the hopper 10 to bring a new carrier into transferring position, the severed end *b* of the carrier just transferred will be withdrawn still farther from the shuttle-box, and this of course, will continue as the hopper further rotates.

From the construction described, it will be noted that upon call for filling replenishment, the rocker arm 36 will be moved contraclockwise into the position indicated in Fig. 1, and will lift the latch 33 from locking engagement with the rod 22, whereupon the latter, under the action of the 120 spring 30, will be moved rearwardly, thereby separating the fixed and movable members of the thread parter into the position indicated in Fig. 1. After the replenishing operation, the lay moves backward and the 125 130

shuttle is picked to the opposite box, whereupon the end of the new filling leading from the securing means or pins 42 and under the hopper stand, will be drawn into the space between the fixed and movable members of the thread parter; and upon the next forward or beatup movement of the lay, the head 27 secured to the rod 22 will be moved by the bunter 29 frontwardly, thereby closing the movable and fixed members of the parter and parting the filling in the position indicated at *a*, Fig. 1. Thus forward movement of the movable parter 23 and its connected rod 22 positions the notch 32 beneath the latch 33, so that after this beatup movement of the lay and parting of the filling as described, the fixed and movable members of the parter will remain in close relation until another call for filling replenishment.

The new filling having been parted in the manner described, it is desirable that that portion of the filling leading from the cloth selvage which still remains intact, shall not be drawn into the shed by the shuttle on a subsequent pick; and to this end there is mounted upon the breast beam, the pneumatic filling end controller 43 which may be of substantially the same character and construction as that described in a prior application filed by me October 29, 1914, Serial No. 869,206. In the present invention, however, the tubular portion 43 of the pneumatic controller is provided with an end rest 44 having a turned-up or lip portion 45 at the end, so that when the piece of filling *c*, Fig. 3, has been parted between the hopper and shuttle-box, as hereinbefore described, it will drop upon the end rest 44 and by the ingoing air currents be sucked into the tube 43. In order that the rest 44 may project sufficiently far rearwardly toward the lay 45*, said lay is provided with a groove portion 46 extending transversely thereof, substantially as indicated in Fig. 3, the construction being such that as the lay beats up, the portion *c* of the new filling after it has been parted between the top of the shuttle-box and the bottom of the hopper stand, will drop upon the rest 44 and be unerringly carried into the suction tube 43 by the ingoing air currents.

When the portion *c* of the new filling is thus engaged by the filling end controller 43 and held therein, by the air currents as described, it will be positioned for the action of the temple thread cutter 47 which, upon a subsequent forward movement of the lay, will sever the new filling at the cloth selvage and permit the part *c*, now bodily free, to move into the controller 43 and be carried out of the loom.

It will be noted from the construction described as a convenient form or embodiment

of the present invention that the new filling end is parted above the shuttle-box, the front wall 46* thereof being indicated in Fig. 3; and that the severed portion *b* will not be in position for engagement by the shuttle. It will also be noted that the loose portion *c*, Fig. 3, will at once be brought under the control of the filling end controller 43 and will be drawn by the air currents thereinto, until the selvage or temple thread parter has acted, whereupon the free piece 75 of filling *c* will be carried out of the loom.

In order that the movable and fixed members 23 and 25 of the parting mechanism shall be limited in their degree of separation, a stop 48 may be provided at the end of the guideway in which the rod 22 is movable, so that the head 23 of the movable member of the parter may contact with and be arrested by the stop 48 when the movable and fixed members of the parter are in 85 their desired separated relation.

It will be evident, of course, that changes may be made in the details of construction which have been described as a convenient form of the present invention, but so far as 90 I am aware, it is new to provide means for parting the new filling in such position with relation to the filling end securing means that the end extending from the securing means cannot be reached by any of the parts 95 liable to carry a portion of said end into the shed.

In the present instance of the invention, the filling parting means is illustrated adjacent the butt ends of the filling carriers 100 in the hopper, and such disposition of the parting means and securing means has been found in practice to be well adapted to the intended purpose, but it is to be understood, of course, that this location of the parting 105 means and securing means is not essential and they may be otherwise disposed relative to the filling carriers, as will be clearly obvious to those skilled in the art.

What is claimed is:—

1. In a filling replenishing loom, the combination of the lay and shuttle-boxes, a hopper for filling carriers, means for securing the ends of the new filling leading from the carriers in the hopper, a selvage thread parter, a thread parter for parting the new filling at a point less distant from said securing means than the distance between said means and the lay, and means between said thread parters for removing the piece of 115 new filling from the loom after it has been parted.

2. In a filling replenishing loom, the combination of the lay and shuttle-boxes, a hopper for filling carriers, means for securing the ends of the new filling leading from the carriers in the hopper, a selvage thread parter, and a thread parter for parting the 125

- new filling at a point between said securing means and the lay and less distant from said securing means than the distance between said means and the lay that the end of the 5 filling leading from said securing means will not be engaged by the lay after it has been parted.
3. In a filling replenishing loom, the combination of the lay and shuttle-boxes, a hopper for containing a supply of filling carriers, means for securing the ends of the filling leading from the carriers in the hopper, and means for parting the new filling between the securing means and shuttle-box 10 at a point less distant from said securing means than the distance between said means and the shuttle-box.
4. In a filling replenishing loom, the combination of the lay and shuttle-boxes, a rotary hopper for containing a supply of filling carriers, securing means movable with the rotary hopper for securing the ends of the filling leading from the carriers in the hopper, means for parting the new filling 15 end after a replenishing operation at a point between the securing means and shuttle-box that the end of the filling leading from the securing means will not reach the shuttle-box, and means for rotating the hopper and causing said securing means to withdraw the filling end from proximity to the lay.
5. In a filling replenishing loom, the combination of a hopper for containing a supply of filling carriers, a stand for said hopper, securing means for securing the ends of the new filling leading from the carriers in the hopper, a thread parter, and means for supporting the thread parter to act upon and part the new filling between the securing 20 means and the top of the shuttle-box that the end of the filling leading from the securing means may not be engaged by the shuttle-box or lay after it has been parted.
6. In a filling replenishing loom, the combination of the lay and shuttle-boxes, a hopper above one of the shuttle-boxes when the lay is in front position to contain a supply of filling carriers, a stand for supporting said hopper, a thread parter for parting the new filling between the hopper and top of the shuttle-box.
7. In a filling replenishing loom, the combination of the lay and shuttle-boxes, a thread parter for parting the new filling at a point above the shuttle-box as the lay moves to front position, a selvage thread parter, and means between the said two thread parters for carrying away the detached piece of new filling.
8. In a filling replenishing loom, the combination of the lay and shuttle-boxes, a rotary hopper carrying a supply of filling carriers, a hopper stand, a new filling end parter carried by the said stand and adapted to part the new filling between the hopper 65 stand and shuttle-box, and means for retaining said parter inoperative until a call for filling replenishment.
9. In a filling replenishing loom, the combination of the lay and shuttle-boxes, a rotary hopper for filling carriers, a hopper stand having a fixed thread parting member, a movable parting member, means for maintaining said parting members in inoperative relation until call for filling replenishment 70 and then permitting said members to become operatively positioned to receive the new filling end between them, and means for causing the parting members to part the filling.
10. In a filling replenishing loom, the combination of the lay and shuttle-boxes, a hopper and hopper stand, a filling end parter to part the new filling end between the hopper stand and top of the shuttle-box, means for holding the filling parter inoperative until a call for filling replenishment and to then free the parter to part the new filling on the beat-up movement of the lay following filling replenishment.
11. In a filling replenishing loom, the combination of the lay and shuttle-boxes, a hopper, securing means for the filling ends leading from the hopper, a thread parter comprising a fixed member and a movable member for the filling ends leading from the hopper, means normally acting to hold the fixed and movable members of the parter in closed relation and rendered operative upon a call for filling replenishment to free the movable member, and means acting upon the movable member as the lay beats up to part the new filling above the shuttle-box.
12. A thread parter for a filling replenishing loom, comprising a fixed member, and a movable member, means normally tending to separate said members, a catch for holding the two members from separation until a call for filling replenishment, means for then tripping the catch, and means for thereafter operating the thread parter to part the new filling above the shuttle-box.
13. A thread parter for a filling replenishing loom, comprising a fixed member, and a movable member, means normally tending to separate said members, a catch for holding the two members from separation until a call for filling replenishment, means for then tripping the catch, means for thereafter operating the thread parter to part the new filling above the shuttle-box, and a thread controller for withdrawing the end of the new filling leading from the cloth selvage.
14. In a filling replenishing loom, a thread parter to part the new filling above the shuttle-box, a selvage thread parter, a pneumatic thread controller having a thread rest between said thread parters to take the piece of new filling from the loom.

15. A thread parter for filling replenishing looms, comprising a fixed member and a movable member, a hopper stand having a guiding portion, a rod carrying the movable member and movable in said guiding portion, a spring normally acting to separate said fixed and movable members, a catch for holding the members in closed relation until call for filling replenishment, and a transverse shaft and arm operated thereby for tripping the catch when the filling is to be changed.

16. In a filling replenishing loom, the combination of the lay and shuttle-boxes, a hopper and hopper stand, a thread parter carried by the hopper stand above the shuttle-box when the latter is in front position, means for securing the ends of the new filling, and means for operating the thread parter to part the new filling above the shuttle-box after a call for filling replenishment.

17. In a filling replenishing loom, the combination of the lay and shuttle-boxes, a hopper for containing a supply of filling carriers, means for securing the ends of the filling adjacent the butt ends of the filling carriers in the hopper, and a cutter above the top of the shuttle-box at the replenishing side of the loom when the lay is in front position to cut the filling.

18. In a filling replenishing loom, the combination of the lay and shuttle-boxes, a hopper for containing a supply of filling carriers, means for securing the ends of the filling adjacent the butt ends of the filling carriers in the hopper, and means located above the top of the shuttle-box at the replenishing side of the loom when the lay is in front position for parting the filling at a point less distant from said securing means

than the distance between said securing means and the shuttle-box.

19. In a filling replenishing loom, the combination of the lay and shuttle-boxes, a hopper for containing a supply of filling carriers, means for securing the ends of the filling adjacent the butt ends of the filling carriers in the hopper, and means for parting the filling above the path of the shuttle-box.

20. In a filling replenishing loom, the combination of the lay and shuttle-boxes, a rotary hopper for containing a supply of filling carriers, and means for parting the filling at a point between the rotary hopper and shuttle-box at the replenishing side of the loom.

21. In a filling replenishing loom, the combination of the lay and shuttle-boxes, a rotary hopper for containing a supply of filling carriers, means for parting the filling at a point between the rotary hopper and shuttle-box at the replenishing side of the loom, and means for rendering said parting means operative on call for filling replenishment.

22. In a filling replenishing loom, the combination of the lay and shuttle-boxes, a hopper for containing wound filling carriers or bobbins, a cutter for parting the new filling, and a support for sustaining the cutter in cutting position above the top of the shuttle-box at the replenishing side of the loom.

In testimony whereof, I have signed my name to this specification, in the presence of two subscribing witnesses.

ALONZO E. RHOADES.
